UNITED STATES PATENT OFFICE.

CHARLES H. SMOOT, OF SOUTH ORANGE, NEW JERSEY, ASSIGNOR TO RATEAU BATTU SMOOT ENGINEERING CORPORATION, OF NEW YORK, N. Y., A CORPORATION OF DELAWARE.

CENTRIFUGAL FLUID-PRESSURE-GENERATING APPARATUS.

1,361,107.

Specification of Letters Patent.

Patented Dec. 7, 1920.

Application filed May 20, 1920. Serial No. 382,995.

To all whom it may concern:

Be it known that I, CHARLES H. SMOOT, a citizen of the United States, and resident of South Orange, in the county of Essex and 5 the State of New Jersey, have invented certain new and useful Improvements in Centrifugal Fluid-Pressure-Generating Apparatus, of which the following is a specification.

10 My invention has for its principal object the production of means whereby a centrifugal pressure creating element is made to produce a fluid pressure which is in proportion to the square of the speed of rotation of the impeller. In the construction of this element, the means I have devised obviates 15 pressure fluctuations, as well as errors or departures between a uniform ratio of speed to pressure.

20 It is well known in the art that a centrifugal pressure creating element such as a centrifugal pump or similar device, produces approximately a fluid pressure in proportion to the square of the speed and that 25 such pressure varies, increasing or decreasing with the quantity of fluid passing through the impeller.

A centrifugal fan or pump is arranged primarily to pass a volume of fluid from a 30 lower to a higher pressure and its features of construction are proportioned for economical power consumption in the production of fluid under pressure. When used as a speed meter, or centrifugal governor, the 35 rotary pressure creating element is not passing any material volume and if proportioned in the same manner as would be a centrifugal pump or blower, the pressure delivered is not strictly in proportion to the speed of rotation and also varies with the quantity of 40 fluid passing, and when such quantity is restricted, a fluctuating pressure unsuitable for metering or regulation is developed.

By means of the pressure creating centrifugal element which I have invented, 45 these disadvantages are obviated and my apparatus produces a pressure free from fluctuations, having a fixed ratio between speed and pressure when no volume is passing 50 through the machine other than a small amount of inevitable leakage.

To obtain this result, I employ an impeller and casing so proportioned that it maintains a definite diameter and radial depth of an-

nular ring of the fluid rotating at the speed 55 of the shaft. I provide means which prevent the impeller communicating a rotary motion to the fluid beyond a predetermined distance inside or outside of the impeller or both. 60

A simple embodiment of one form of my invention will suffice to make clear to those skilled in the art the manner in which the improvement is applied in practice.

The accompanying drawings—Figures I, 65 II, and III—show Fig. I, a vertical cross-section through my apparatus; Fig. II, a view in vertical plan of wheel 2 of Fig. I; and Fig. III, a view in vertical plan of wheel 2 modified. 70

Referring to Figs. I and II shaft 1 revolves in journal 3. 2 is a wheel rigidly attached to shaft 1 by means of nut 30. 6—6 are projecting vanes attached to wheel 2. 5—5 is a ring having radial perforations 31—31. 75 Wheel 2 rotates in casing 7, which is closed by cover plate 4. Annular chamber 8 is partitioned by ring 5—5. 9 is a pipe for the discharge of fluid from annular chamber 8 to point of use. 10 is a cylindrical shell provided with perforations 12 and 13. Fluid enters my device through perforations 12 in the outer portion of cylindrical shell 10 and then is discharged to vanes 6—6 of wheel 2 through perforation 13 located in the inner 80 portion of shell 10.

In Fig. III, wheel 2 is shown, with symbols corresponding to Fig. II. Wheel 2 has a shroud 32 with radial perforations 33—33—33. 85

The operation of my apparatus is substantially as follows: Fluid is introduced through radial perforations 12 and 13 into the rotating element comprised of wheel 2 and vanes 6. The fluid is discharged by vanes 6 in 95 such a manner that it rotates in a relatively small space between the end of vanes 6 and ring 5. The air escaping through ring 5 is discharged through radial perforations 31—31 in such a way that in the outer portion of annular chamber 6 there is no appreciable rotary motion of the fluid. 100

It will be seen that the fluid within shell 10 is nowhere exposed to moving metal and can acquire no tendency to rotate by frictional contact with the impeller, as is the case with centrifugal pumps and the like. 105

The function of ring 5 and perforations

31—31 is to destroy the rotary motion of all fluid leaving the impeller after it has reached this ring, without conversion to pressure. This is the reverse of what is done 5 in the construction of a pump, in which—for reasons of economy—all velocities, especially those of discharge from the impeller are converted into pressure. Ring 5 destroys the rotary velocities with corresponding loss of energy and with almost complete 10 non-conversion into pressure, thus obliging the apparatus to create pressure only by virtue of the rotating ring of fluid of definite internal and external diameter.

15 In Fig. III, wheel 2 carries a shroud 32 with perforations 33—33. By means of this construction, the influence of ring 5 to set up internal swirls and eddies within the volume of fluid located from periphery of vanes 20 6 to ring 5, is reduced—a further source of error overcome.

I have constructed a centrifugal impeller, which is not suitable as a pump displacing volume with an efficient consumption of 25 power, but I have provided an impeller and casing which creates a pressure accurately in proportion to its speed of rotation. This result is accomplished by means through 30 which I confine a rotating ring of fluid which has a definite inside and outside diameter, that can be displaced in its path from cylindrical shell 10 to ring 5 only by means of a radial flow. In consequence of 35 having defined the external and internal diameters of the ring of rotating fluid, the pressure generated is made a definite quantity.

It is obvious to those skilled in the art 40 that many different shapes of impeller may be employed and that a number of means are available in the art to obtain similar results to those shown in the embodiment of my invention, which are accomplished by ring 5 with radial perforations 31—31, 45 and shell 10 with perforations 12—12 and 13—13.

While I prefer to use both internal and external perforated inlets and outlets, I give greater importance to ring 5. Cylindrical 50 shell 10 may be omitted without introducing

serious errors in the relation between pressure and speed. The annular ring 5, or its equivalent, limits positively the outer diameter of fluid rotation and as such a limit is an essential.

55

I claim:

1. In a centrifugal fluid pressure generating apparatus adapted to produce accurately a pressure in proportion to the square of the speed of rotation, an impeller to transmit 60 rotating velocities to a fluid and means to restrict the rotating fluid to a ring of definite internal and external diameter.

2. In a centrifugal fluid pressure generating apparatus adapted to produce accurately 65 a pressure in proportion to the square of the speed of rotation, an impeller to transmit rotating velocities to a fluid and a stationary perforated ring restricting the path of the rotating fluid.

70 3. In a centrifugal fluid pressure generating apparatus adapted to produce accurately a pressure in proportion to the square of the speed of rotation, an impeller and chamber adapted to receive the fluid discharged by 75 the impeller, and a stationary ring located in said chamber having radial passages for the fluid flow.

4. In a centrifugal fluid pressure generating apparatus adapted to produce accurately 80 a pressure in proportion to the square of the speed of rotation, means to impart rotating velocities with substantially complete non-conversion into pressure.

5. In a centrifugal fluid pressure generating apparatus, an impeller, means to introduce fluid radially in the impeller inlet and means to discharge fluid radially delivered by the impeller.

90 6. In a centrifugal fluid pressure generating apparatus adapted to produce accurately a pressure in proportion to the square of the speed of rotation, a shrouded impeller having perforations for radial discharge of the fluid passing through the impeller, a chamber adapted to receive the fluid discharged by the impeller and a stationary ring located in said chamber having radial passages for the fluid flow.

CHARLES H. SMOOT.
